UNITED STATES PATENT OFFICE.

KATHERINE O'KANE, OF PHILADELPHIA, PENNSYLVANIA.

DUPLICATING-MACHINE.

No. 901,121.

Specification of Letters Patent.

Patented Oct. 13, 1908.

Application filed May 28, 1908. Serial No. 435,497.

To all whom it may concern:

Be it known that I, KATHERINE O'KANE, of Philadelphia, in the State of Pennsylvania, have invented a certain new and useful Improvement in Duplicating-Machines, whereof the following is a specification, reference being had to the accompanying drawings.

My improvement is particularly applicable to a machine of the type known commercially as the "multigraph", comprising a rotary cylinder having a series of undercut channels in its perimeter extending parallel with its axis to receive complementary shaped flanged type which said cylinder presents in opposition to a plane reciprocatory platen. As ordinarily constructed, the only means with which such a machine is provided for underscoring the word imprints consists of type fitted to the channels and having dash faces. Consequently, it is impossible to make with such machines imprints wherein single spaced lines of words are underscored, because the word lines must be double spaced to afford a channel between them to receive said underscore type.

Therefore, it is an object of my invention to provide such a machine with means for underscoring single spaced lines of words, and, the form of my invention hereinafter described comprises a rotary cylinder provided with channels extending in its perimeter parallel with its axis; flanged type fitted in said channel in single spaced relation, and an underscore rule strip held by and between said flanged type in said channels, independently of said cylinder. I prefer to form said underscore strips of resilient sheet metal, such as spring steel which is initially curved, so that when straightened by engagement between the type in the cylinder such strips frictionally engage said type.

My invention comprises the various novel features of construction and arrangement hereinafter more definitely specified.

In the drawings; Figure I, is a side elevation of a rotary printing cylinder and reciprocatory plane platen, such as are employed in a machine of the type specified. Fig. II, is a fragmentary plan view of a portion of said cylinder with letter-type and underscore strips set therein. Fig. III, is an end view of the elements shown in Fig. II. Fig. IV, is a perspective view of a detached

underscore type strip. Fig. V, is a side view of one of the underscore type of ordinary construction, having flanges to engage the channels in the cylinder.

In said drawings; the rotary printing cylinder 1, has the undercut channels 2, extending in its perimeter parallel with its axis, and, each type 3, 4, and 5, is provided with flanges 6, complementary to and fitted in said channels. When said flanged type are fitted in single spaced relation as shown in Figs. II, and III, there are interstices 7, extending between them parallel with the axis of the cylinder 1, and of such width as to receive underscore strips 8. However, it may be observed that said strips do not enter said channels 2, in the printing drum, or engage the latter, but are maintained type high by the ridges on said printing drum between said channels 2, and are held solely by frictional engagement between the flanged type which are engaged in said channels.

As indicated in Fig. IV, a strip 8, formed of spring steel may be initially curved but such a curved strip is straightened when fitted between the flanged type as shown in Fig. II.

When the type have been assembled in the cylindrical printing drum 1, in the desired relation, the inked ribbon 12, is drawn over the type faces and secured by connection with the rollers 13 and 14, which are mounted in said cylinder as indicated in Fig. I, so that when a sheet of paper is interposed between the platen and said cylinder, and said cylinder turned until the platen is shifted to the position shown in dotted lines in Fig. I, said sheet is imprinted with an imprint made from said type through said inked ribbon and the words in single spaced relation are underscored without the employment of the ordinary underscore type 5, shown in Fig. V. Although said flexible underscore strips 8, may be employed to underscore letter type which are in double spaced relation, in which case they may be held between the letter type 3, and blank type 4, as shown in Fig. II, it is more convenient to employ the ordinary underscore type 5, when the matter is set in double spaced relation.

I do not desire to limit myself to the precise details of construction and arrangement above described, as it is obvious that various

modifications may be made therein without departing from the essential features of my invention, as defined in the appended claims.

I claim:—

- 5 1. In a duplicating machine, the combination with a rotary printing drum having a plurality of undercut channels in its periphery; of type having flanges fitted in said channels; and, an underscore strip held between said flanged type, independently of said drum.
- 10 2. In a duplicating machine, the combination with a rotary printing drum having a plurality of undercut channels extending parallel with its axis in its periphery; of type fitted in said channels; and, an underscore strip held by and between the type, independently of said drum.
- 15 3. In a duplicating machine, the combination with a rotary printing drum having a plurality of undercut channels extending parallel with its axis in its periphery; of type having flanges fitted in said channels in single spaced relation; and an underscore rule strip held between said flanged type, independently of said drum.
- 20 4. In a duplicating machine, the combination with a rotary printing drum; having a plurality of undercut channels extending parallel with its axis in its periphery; of type having flanges fitted in said channels
- 25
- 30

in single spaced relation; and, a flexible resilient underscore rule strip held by and between said flanged type, independently of said drum.

35 5. In a duplicating machine, the combination with a rotary printing drum; of type carried by said drum; an underscore rule strip held by and between said type; and, means distinct from said type maintaining said rule type high.

6. In a duplicating machine, the combination with a rotary printing drum; of type carried by said drum; an underscore rule strip held by and between said type; and, 45 means distinct from said type maintaining said rule type high, comprising a ridge on said drum.

7. In a duplicating machine, the combination with a rotary printing drum; of type 50 carried by said drum; an underscore rule strip held by and between said type; and, means distinct from said type maintaining said rule type high, comprising a ridge on said drum extending parallel with said strip. 55

In testimony whereof I have hereunto signed my name at Philadelphia, Pennsylvania, this ninth day of May, 1908.

KATHERINE O'KANE.
